corporation of New York

Application June 2, 1945, Serial No 119,865

Term of patent 14 years

(Cl. D58—8)

To all whom it may concern:

Be it known that I, Andre Sussman, a citizen of the United States, residing at 530 E. 90th Street, New York city, in the county of New York and State of New York, have invented a new, original, and ornamental Design for a Bottle, of which the following is a specification, reference being had to the accompanying drawing, forming part thereof.

In the drawing:

Fig. 1 is a side elevational view of a bottle showing my new design;

Fig. 2 is a front elevational view.

Fig. 3 is a front elevational view with top separated, and shown in section.

Fig. 4 is a top plan view.

I claim:

The ornamental design for a bottle, substantially as shown.

ANDRE SUSSMAN.
